Patented Jan. 17, 1922.

FIG. 1

FIG. 2

FIG. 3

A technical line drawing of a mechanical assembly, possibly a gear or sprocket. The drawing shows a central horizontal shaft with various parts attached. Key features include a central gear-like section with a hub, a side plate with a slot, and a housing on the right. Numerous components are labeled with numbers: 20, 19, 7, 26, 18, 16, 15, 18, 37, 13, 30, 34, 36, 23, 22, 17, 11, 28, 32, 31, 33, 12, 34, 30, 7, 35, 24, 25, and 32. The numbers are distributed across the various parts of the assembly, including the main body, the central gear, and the side components.

UNITED STATES PATENT OFFICE.

ARTHUR J. CANFIELD AND ERNEST R. VIBERG, OF MONTREAL, QUEBEC, CANADA.

TRUCK BOLSTER.

1,403,588.

Specification of Letters Patent. Patented Jan. 17, 1922.

Application filed November 23, 1920. Serial No. 425,974.

To all whom it may concern:

Be it known that we, ARTHUR J. CANFIELD, a citizen of the United States of America, and ERNEST R. VIBERG, a subject 5 of the King of Great Britain, and both residents of the city of Montreal, in the Province of Quebec and Dominion of Canada, have invented certain new and useful Improvements in Truck Bolsters, of which 10 the following is a full, clear, and exact description.

This invention relates to improvements in railway car truck bolsters, and the object of the invention is to provide a bolster of simplified construction and increased strength.

A further object is to provide a bolster constructed as nearly as possible altogether of pressed parts.

A still further object is to provide a bolster 20 in which the centre plate and side bearings are an integral part of the bolster formed in one piece with the main member of the bolster.

The invention resides briefly in providing 25 a bolster having the compression member thereof pressed of a single piece and preferably including the centre and side bearings. The tension member of the bolster may be a pressing or may be an ordinary 30 channel of sufficient width to receive between its flanges the ends of the compression member and adapted at its ends to be lapped over the ends of the compression member.

In the drawings which illustrate the invention;—

Fig. 1 is a plan view of a bolster formed according to this invention.

Fig. 2 is a side elevation of the bolster partly in vertical longitudinal section.

Fig. 3 is a view showing at the left hand side a cross section at the centre of the bolster and at the right hand side a cross section on the line 3—3, Figure 2.

Fig. 4 is a half cross section on the line 45 4—4, Figure 2.

Fig. 5 is a view similar to Figure 2 illustrating modifications of construction.

Fig. 6 is a cross sectional view similar to Figure 3.

Fig. 7 is a half cross section on the line 50 7—7, Figure 5.

Referring more particularly to the draw-

ings, 11 designates the compression member and 12 the tension member of a bolster. The compression member is, roughly speaking, 55 channel-shaped in cross section but is of increased width intermediate its ends to accommodate the raised annulus 13 constituting the centre bearing. The depth of the compression member is decreased toward the 60 ends, as shown at 14, so that the ends of the member may be received between the flanges of the channel-shaped tension member 12 where the two members converge and so that the top or web of the compression member 65 will lie at the ends of the bolster approximately at the same level as the edges of the compression member flanges.

Intermediate the centre and ends, the compression member may be provided with an 70 upwardly extending transverse rib or boss 15, which constitutes the side bearings or a seat for a special side bearing member 16. At this point, a filler 17 is provided between the compression and tension members and 75 may be connected to the compression member by the same rivets which connect the side bearing 16. To give stiffness to the compression member, a suitable number of ribs 18 are struck up from the surface thereof extending in decreasing height from the centre bearing 13 substantially to the ends and intersecting the transverse rib 15 forming the side bearing.

It will be noted that both the compression and tension members are somewhat of the pan or bath-tub type, that is to say, they are closed at the ends by walls 19 and 20 respectively extending between the webs thereof. The end walls 19 of the compression 80 member abut the end walls 20 of the tension member. In making up the bolster, the end walls 20 of the compression member may be of greater depth than the side walls, as indicated at 20^a, Figure 2, and after the compression member is in place, this end wall may be pressed or forged down over the end of the compression member to increase the security with which the compression member is seated in and against the end of the tension member.

A spring seat 21 is provided extending under the end of the compression member and upwardly outside the end thereof, the

plane of this seat being at an angle to the plane of the tension member, as clearly shown, and the wedge-shaped space between the tension member and seat being occupied by a filler 22. The same rivets 23 which hold the compression and tension member ends together also hold the outer end of the spring seat, while the inner end of the spring seat is held by the same rivets 24 which assist in holding the filler 17. Additional rivets 25 may be provided if desired to secure the filler 17. Vertical bearings or shoes 26 are attached adjacent the ends for engagement with the truck side frame. An aperture 27 is provided near the end of the compression member to enable the insertion or heading of the various rivets around the end of the bolster.

The king post 28 holding the compression and tension members apart at their centres is preferably a casting provided with a tubular neck 29 to receive the king pin and extending through an aperture 30 in the compression member. The king post itself 25 comprises a pair of spaced side plates 31 connected by top and bottom plates 32, which are stiffened and braced by webs 33. The king post is designed to fit snugly between the webs of both compression and tension members and is thereby held against lateral movement without placing reliance upon the engagement of the bearing member 29 in the compression member.

In the form shown in Figure 5 the construction of the compression member is similar with that already described, with the principal exception that the aperture 30 is surrounded by an integral upstanding wall or flange 34, which forms a bearing for the king pin. It will be noted in Figure 2 that the depth of the webs of the compression member increases from the centre toward the ends, whereas in Figure 5 the depth of the webs is uniform. The tension member 45 is of the same construction shown in Figure 2, with the exception that it tapers from the centre toward the ends and lacks the bent over portion 20^a shown in Figure 2. The spring seat 21^a is provided with an upset portion or boss 35 which bears against the under side of the tension member and replaces the filler shown in the other construction. The king post 28^a differs from the king post shown in Figure 2, in that it lacks the upwardly projecting neck 29 engaging the compression member. The holding effect of this neck is performed by an upturned annular flange 36 which engages in the recess 37 on the under side of the compression member produced by the formation of the annular rib 13. Another difference resides in the bearings 26^a which are lugs turned up from the spring seat 21^a and integral therewith instead of separate members as in Fig. 2.

The compression member including the centre bearing 13 and side bearings 15 is pressed from a single piece of metal, while the tension member is similarly pressed from a single piece of metal. The location and form of the various parts is such that they may be connected together with a minimum number of rivets, thereby greatly reducing the labor cost in manufacturing bolsters. All parts of the bolster being forged or pressed from plates or rolled sections combine great strength with light weight. The formation of the centre bearing integral with the compression member ensures against looseness, rattling or separation of the centre bearing from the bolster, such as occurs at the present time, and also greatly simplifies the process of manufacture and reduces the weight.

Having thus described our invention, what we claim is;—

1. A sheet metal bolster having integral, annular, transverse and longitudinal portions pressed therefrom to form respectively a central bearing, side bearings, and longitudinal reinforcing ribs extending between said bearings.

2. In a bolster, compression and tension members of channel section, the ends of the compression member being embraced by the ends of the tension member, and end plates closing the ends of the compression and tension members and abutting one another.

3. In a bolster, compression and tension members of bath-tub type, the ends of the compression member being received in and abutting against the ends of the tension member and spring seats under the tension member overlapping the ends thereof, and a rivet connecting adjacent ends of the compression and tension members and the adjacent spring seat together.

4. In a bolster, compression and tension members of channel section arranged face to face, a corrugation on the compression member forming a side bearing seat, a filler between the members fitting into the concave under surface of the seat, a side bearing, and a rivet holding said side bearing and filler to the compression member.

5. In a bolster, compression and tension members, the tension member being inclined from the centre toward the ends at an angle to the horizontal, a spring seat secured under each end of the tension member and located in a substantially horizontal plane whereby a wedge-shaped space is formed, and a support for said seat located in said space.

6. In a bolster, compression and tension members of channel section arranged with their concave sides facing, and a strut spacing said members apart at their centres, said strut being retained in position

solely by interengagement with the members.

7. In a bolster, compression and tension members, the compression member having an opening in its lower surface, a strut spacing said members apart at their centres, and a projection from said strut entering

the opening in the compression member and holding the strut in position.

In witness whereof, we have hereunto set 10 our hands.

ARTHUR J. CANFIELD.
ERNEST R. VIBERG.
